UNITED STATES PATENT OFFICE.

ALMANZER GAINES, OF MENDON, MICHIGAN, ASSIGNOR OF THREE-FOURTHS
TO OTTO W. SEEB AND CHARLES W. SEEB, OF SAME PLACE.

PRINTING-PRESS.

SPECIFICATION forming part of Letters Patent No. 577,848, dated March 2, 1897.

Application filed July 29, 1896. Serial No. 600,985. (No model.)

To all whom it may concern:

Be it known that I, ALMANZER GAINES, a citizen of the United States, residing at Mendon, in the county of St. Joseph and State of Michigan, have invented a new and useful 5 Printing-Press, of which the following is a specification.

This invention relates to printing-presses, and has reference to that class in which a 10 horizontal reciprocating type-bed is employed in connection with a revolving impression-cylinder.

The object of the present invention is to provide means for causing the cylinder to operate with an intermittent motion, revolving 15 as the type-bed moves forward and remaining stationary as the bed is retracted, thus economizing the power required to drive the machine.

20 The invention also has reference to the manner of mounting the device which contributes to the above end and to the means for moving the inking-rollers onto the ink-plate as the type-bed reaches the limit of its 25 backward movement.

Other objects and advantages of the invention will appear in the course of the ensuing description.

The invention consists in certain novel features and details of construction and arrangement of parts, as hereinafter fully described, 30 illustrated in the drawings, and finally embodied in the claims hereto appended.

In the accompanying drawings, Figure 1 is 35 a side elevation of a cylinder-press constructed in accordance with the present invention. Fig. 2 is a plan view of the same. Fig. 3 is a longitudinal section thereof. Fig. 4 is a cross-section through the machine. Figs. 5 and 6 are detail cross-sections showing modifications in the manner of mounting the reciprocating type-bed.

Similar numerals of reference designate corresponding parts in the several figures of the 45 drawings.

Referring to the accompanying drawings, 1 designates the press-frame, upon which is mounted a horizontal and longitudinally-reciprocating type-bed 2. Above the type-bed 50 2 is located the revolving impression-cylinder 3, extending transversely across the machine

and mounted in fixed bearings 4, located intermediate the length of the press-frame. The type-bed 2 may be slidingly mounted on the press-frame in one of several ways. It may 55 either be provided on its under side with V-shaped longitudinal ribs 5, working in channel-guides 6, as shown in Fig. 4, or it may be provided upon its under side with carrying-rollers 7, having V-shaped rims, as shown in 60 Fig. 5, or grooved, as shown in Fig. 6, the said rollers operating upon and in connection with correspondingly-formed rails or guides, thus insuring the working of the type-bed in a perfectly-true line. 65

The type-bed is reciprocated by means of an oscillating toothed segment 8, which meshes with a longitudinal rack-bar 9 on the bottom of the type-bed. The segment 8 is fulcrumed on the shaft 10, mounted near the base of the 70 machine-frame in suitable bearings, and is actuated through the medium of an interposed link 11 by a revolving spur-gear 12, which is in turn actuated by means of a spur-pinion 13 on the driving-shaft 14 of the machine. The link or connecting-rod 11 is journaled on a wrist-pin on the spur-gear 12 at a suitable distance from the center, so that as 75 said wheel revolves the link is caused to oscillate the segment 8, and the latter in turn 80 to reciprocate the type-bed. The driving-shaft 14 may be actuated in any suitable manner.

The type-bed is provided at one side with a rack-plate 15, which meshes with a multi-lated spur-gear 16 on the adjacent end of the cylinder 3. The teeth of the rack-plate and gear are so regulated and numbered that the forward movement of the type-bed will impart exactly one revolution to the cylinder 90 and bring the gap in the gear-teeth or that part of the spur-wheel in which the teeth are omitted into the lowermost position, so that as the type-bed is retracted the teeth of the gear 16 will not be engaged by the teeth of 95 the rack-plate 15, thus leaving the impression-cylinder stationary. In order to insure the complete revolution of the cylinder in the forward movement of the type-bed, the latter is provided at its rear end with a hook or projection 17, which, as the type-bed reaches the forward limit of its throw, contacts with a 100

pin 18 on the cylinder and moves the latter sufficiently to bring the gap in the teeth to the lowermost point, as shown in Fig. 1.

19 designates a longitudinal rock-shaft having its ends reduced and journaled in suitable bearings 20, secured to one side of the frame 1. This rock-shaft is arranged at one end of the cylinder and is provided intermediate its ends with an arm 21, having an inwardly-extending projection or stud 22, adapted to enter between the opposing faces or shoulders of a pair of segmental cam projections 23, located at one end of the cylinder and near the periphery thereof. These cam projections have reversely-inclined working faces, so that the projection or stud 22 may ride thereon until it drops in between the opposing faces of said projections 23 and locks the cylinder against further rotation. A spring 24 surrounds the rock-shaft 19 and gives the arm 21 an inward pressure, so that the stud 22 will automatically drop in between the cam projections 23 and hold the cylinder locked, as shown in Fig. 1. The locking of the cylinder occurs at the point where the type-bed reaches the limit of its forward movement.

In the return movement of the type-bed a laterally-projecting cam 25 on the type-bed 30 engages under the inwardly-projecting end 26 of a second arm 27 on the rock-shaft 19, thus serving to rock said shaft against the tension of the spring 24, moving the stud 22 out of engagement with the cylinder and leaving the latter free to revolve. The rock-shaft is held locked in this latter position by means of a pivoted latch 28, fulcrumed on the machine-frame and having a lip 29, which engages a catch projection or lip 30 on the rock-shaft, as clearly shown in Fig. 4. The type-bed is provided at one end with a gravity-pawl 31, which just previous to the type-bed 35 reaching the limit of its return movement slips under the pin 18 on the cylinder, whereupon as the type-bed starts forward again the said pawl 31 engages behind the pin 18 and rotates the cylinder sufficiently to bring the teeth of the gear-wheel 16 into mesh with the rack-plate 15, thus causing the cylinder to 40 make another revolution, the paper being fed 45 forward from the feed board or table 32 at the same moment and passing between the cylinder and bed, where it is printed in a manner well understood. Just as the type-bed 50 reaches the forward limit of its movement a hook or finger 33 at the rear end of the bed passes under and engages the inwardly-projecting end 34 of the latch 28, lifting said latch out of engagement with the rock-shaft 55 55 and allowing the spring 24 to throw the arm 21 inward for locking the cylinder.

The ink-roller carriage consists of parallel arms 35, journaled on pintles 35^a, projecting inward from the frame and connected at top and bottom by suitable cross-bars 36. These arms 35 are slotted at their upper ends to receive the spindle of the inking-roller 37, and

the lower cross-bar 36 has connected to it one end of a rod 38, which extends back to an upright lever 39, fulcrumed at its lower end on 70 the press-frame and having its upper end arranged in the path of the type-bed. The type-bed just previous to reaching the limit of its return movement strikes against the lever 39, thereby oscillating the arms 35 and causing 75 the inking-roller 37 to be moved onto the ink-plate 40 at the forward end of the type-bed, where said roller receives its supply of ink and afterward returns to its normal position when the type-bed starts forward by the action of a spring 41, having one end connected to the cross-bar 36 and the opposite end to the press-frame.

The advantages gained by mounting the ink-rollers in a reciprocating carriage are 85 economy in both power and floor-space. Were the rollers held in a stationary rack the bed of the press would be required to have sufficient throw to carry the ink-plate under the rollers at each reciprocation, and in that 90 case the cylinder would have to be larger and the bed-rack longer to perform the function. Thus by my construction I can use a smaller cylinder and a shorter bed and rack, and by this arrangement I save the extra power which 95 would be required to revolve a larger cylinder, and I save the floor-space which would be required for a longer press frame and rack.

From the foregoing description it will be seen that the impression-cylinder has an intermittent motion, revolving as the type-bed moves forward and remaining stationary as the type-bed is retracted. The particular locking and unlocking mechanism described insures the accurate working of the cylinder 105 and prevents it from moving from its correct position. This greatly facilitates the work and economizes in the power required to drive the press.

It will be understood that the several parts 110 of the press described are susceptible of changes in the form, proportion, and minor details of construction, which may accordingly be resorted to without departing from the spirit or sacrificing any of the advantages 115 of this invention.

Having thus described the invention, what is claimed as new is—

1. In a printing-press, the combination with a reciprocating type-bed, of an intermittently-rotated impression-cylinder having a spur gear-wheel at one end, and carrying a pair of cams on its face, and a rock-shaft journaled at right angles to the cylinder on the machine-frame, said rock-shaft provided with an inwardly-extending stud or stop, and means for throwing the stud between the pair of cams 120 to hold the cylinder against rotation, substantially as described.

2. In a printing-press, the combination with a reciprocating type-bed, of an intermittently-rotating impression-cylinder having a spur gear-wheel at one end thereof meshing with a rack on the type-bed, said gear-wheel be- 125

- ing mutilated and provided with a double cam on its face, a spring-actuated rock-shaft journaled on the frame and carrying a stop which is projected between the cams for holding the cylinder stationary during a portion of the throw of the type-bed, a cam 25 on the type-bed, and an arm on the rock-shaft coöperating with the said cam for withdrawing the stop, substantially as described.
- 10 3. In a printing-press, the combination with a reciprocating type-bed, of an intermittently-revolving impression-cylinder having a spur gear-wheel at one end thereof in mesh with a rack on the type-bed, said gear-wheel being mutilated and provided with a double cam on its face adjacent to the mutilated portion of the gear-wheel, a rock-shaft journaled on the frame, a stop on the rock-shaft, automatic means for throwing the stop between the cams and withdrawing it therefrom, a pin 18 on the gear-wheel in line with the opening between the cams, and the type-bed having a hook 17 at one end thereof to catch the pin, for the purpose described.
- 15 4. In a printing-press, the combination of a reciprocating type-bed, carrying a rack, an intermittently-revolving impression-cylinder having a mutilated spur gear-wheel at one end in mesh with the rack, a double cam on said wheel, a spring rock-shaft mounted on the frame at the side of said wheel, and provided with a stop, automatic means for throwing the stop between the cams and for with-

drawing it therefrom, a pin on the gear-wheel in line with the opening between the cams, 35 and the type-bed carrying a hook 17 at one end and a gravity-pawl 31 at the other, for the purpose described.

5. In a printing-press, a reciprocating type-bed, and an intermittent impression-cylinder, 40 in combination with a rock-shaft having an arm for engaging and locking said cylinder, a spring for actuating said rock-shaft, a latch for engaging said rock-shaft and holding said arm away from the cylinder, and a projection 45 or finger on the type-bed for lifting the latch out of engagement with the rock-shaft, substantially as described.

6. In a printing-press, a reciprocating type-bed carrying an ink-plate, and an impression-cylinder, in combination with an ink-roller carriage fulcrumed intermediate its ends, an inking-roller carried thereby, an upright lever having one end arranged in the path of the type-bed so as to be actuated thereby, and 50 a connecting-rod interposed between said lever and the ink-carriage, all arranged substantially as and for the purpose described. 55

In testimony that I claim the foregoing as my own I have hereto affixed my signature in 60 the presence of two witnesses.

ALMANZER GAINES.
